REAR VIEW PROJECTION SCREEN

Martin W. Swithinbank, New York, N.Y., assignor to
Avmar Visuals Inc., New York, N.Y., a corporation of
New York

Filed Sept. 28, 1965, Ser. No. 87,210

Term of patent 7 years

(Cl. D61—1)

The figure is a plan view of a rear view projection screen, showing my new design. The screen is of a thickness and construction conventional to photographic rear-projection screens.

I claim:

The ornamental design for a rear view projection screen, as shown and described.
